UNITED STATES PATENT OFFICE.

JAMES CLARKE HAGEY, OF CHICAGO, ILLINOIS, ASSIGNOR OF ONE-HALF TO THE CABLE COMPANY, OF CHICAGO, ILLINOIS, A CORPORATION OF ILLINOIS.

EXPRESSION DEVICE FOR AUTOMATIC MUSICAL INSTRUMENTS.

1,422,969.

Specification of Letters Patent.

Patented July 18, 1922.

Application filed March 1, 1918. Serial No. 219,879.

To all whom it may concern:

Be it known that I, JAMES CLARKE HAGEY, a citizen of the United States, residing at Chicago, in the county of Cook and State of Illinois, have invented new and useful Improvements in Expression Devices for Automatic Musical Instruments, of which the following is a full, clear, concise, and exact description, reference being had to the accompanying drawing, forming a part of this specification.

My invention relates to an expression-device for automatic musical instruments.

One of the objects of my invention is to provide an improved sheet-controlled automatic musical instrument, in which sheet-controlled means are provided for emphasizing one expression part of a musical composition, such as the solo, with respect to another part thereof, with means for varying the tone-volume or tonal power of one of said parts with respect to the other. A further object of my invention is to provide an improved sheet-controlled automatic musical instrument, in which two different expression-devices are controlled from the same tracker-opening. A further object of my invention is to provide an improved sheet-controlled automatic musical instrument, in which two different expression-devices are controlled from the same music-sheet perforations. A further object of my invention is to provide an improved expression-device for automatic musical instruments in which a regulator acts to mechanically adjust parts of the instrument to limit the movement of the note-sounding mechanism. A further object of my invention is to provide an improved automatic sheet-controlled musical instrument, in which a movable expression-device is connected with a plurality of openings in the tracker and controlled by the volume of air admitted through the tracker-openings. Further objects will appear from the detailed description to follow and from the appended claims.

While shown in connection with a player-piano, the invention may be used, where applicable, upon other mechanical musical instruments.

In the drawings, in which one embodiment of my invention is shown—

Figure 1 is a front elevation of a sheet-controlled pneumatic player-piano embody-

ing my invention, parts being broken away to show the interior construction, and the section being substantially on the line 1—1 of Fig. 2;

Fig. 2 is a section, substantially on the line 2—2 of Fig. 1;

Fig. 3 is a detail sectional view, showing a valve for controlling an expression-device;

Fig. 4 is a section, on the line 4—4 of Fig. 3;

Fig. 5 is an enlarged elevational view of part of the tracker and the associated tubes;

Fig. 6 is an enlarged sectional view, on the line 6—6 of Fig. 2;

Fig. 7 is a vertical transverse section of a player-piano, showing another form of my invention;

Fig. 8 is a vertical, longitudinal, sectional view, somewhat diagrammatic in nature, of the player-piano shown in Fig. 7;

Fig. 9 is a vertical, transverse, sectional view of the primary-valve construction of the expression-device;

Fig. 10 is a horizontal sectional view, on the line 10—10 of Fig. 9;

Fig. 11 is a front elevation of a portion of the tracker and music-sheet.

Fig. 12 is a plan view, on an enlarged scale, of a portion of the mechanism associated with the music-spool;

Fig. 13 is a detail of construction; and

Figs. 14 and 15 are views of an end portion of the music-spool.

Referring now to the drawings in general, the player-piano shown comprises a casing

10, a piano-action 11, a player-action 12, a selector-mechanism 13, an air-pump 14, an expression-device 15 for controlling the air-pressure in the player-action, and a solo-action 16 whereby the solo part of a musical

composition may be emphasized with respect to the accompaniment part. The parts thus far mentioned may be of any suitable construction and need not be described in minute detail. The expression-device 15

may be substantially the same as that shown in my Patent No. 1,359,698, dated Nov. 23, 1920. The piano-action 11, the player-action 12, the selector-mechanism 13, and the solo-action 16 may be substantially the same as those shown in Klugh Patent No. 1,261,553,

dated April 2, 1918. The player-action 12 comprises a series of pneumatics 17, one for

actuating each unit of the piano-action, each of the pneumatics 17 being controlled through one of the openings 18 in the tracker 19 by means of one of the tubes 20.

5 The selector-mechanism 13 comprises the roll-box 21, in which are mounted the tracker 19, the take-up roll 22, and the music spool 23.

The air-pump 14 comprises a plurality of 10 bellows 24 driven from a motor 25, the bellows 24 acting to draw air from the action wind-chest through the conduits 26 and 27 and acting to withdraw air from the expression-device 15 through the conduit 28.

15 The expression-device 15 is connected by means of four tracker-tubes 29 with openings 30 in the tracker 19, and, as described in my Patent No. 1,359,698, referred to above, is so constructed as to admit air more 20 or less freely into the conduit 28, the degree of freedom with which air is admitted depending on which one of the tracker-openings 30 is uncovered. If none of the tracker-openings 30 are uncovered, air is admitted

25 with the greatest degree of freedom to the conduit 28. If the right-hand tracker-opening 30 (as shown in Fig. 5) is uncovered, air is admitted to the conduit 28 with a lesser degree of freedom. If the second

30 from the right-hand tracker-opening 30 (Fig. 5) is uncovered, air is admitted to the conduit 28 with a still lesser degree of freedom, and so on with the other two openings, air being admitted with the least degree of 35 freedom when the left-hand tracker-opening 30 is uncovered.

The more freely air is admitted to the conduit 28, the less will be the rarefaction of the air in the conduit 26, and, consequently, 40 in the wind-chest of the player-action.

The solo-action 16 comprises a series of pneumatics 31, each having, connected therewith and actuated thereby, a rest or abutment 32 located in position to engage two 45 adjacent hammer-heads 33 of the piano-action 11; and a swinging support 34 on which the pneumatics 31 are mounted. Each pneumatic 31 is controlled through two adjacent tracker-openings 35 by means of one of the 50 tracker-tubes 36. Each tracker opening 35 is so located, with respect to one of the tracker-openings 18, that a wide perforation in the music-sheet may uncover both the tracker-opening 35 and the corresponding 55 tracker-opening 18 and a narrow perforation may uncover only the tracker-opening 18.

The support 34 is pivotally mounted at 37 and is actuated by means of a push-rod 38 60 slidable in suitable guides 39, the upper end of the push-rod 38 engaging an arm 40 secured to the swinging support 34. There are two separate controlling means for actuating the push-rod 38: First, a pneumatic toggle-mechanism 41, which acts to place the

solo-action in operative position when the pump 14 is started; and, second, an expression-device 42, which acts on the push-rod 38 to vary the operative position of the solo-action 16 while a selection is being played. 70

The pneumatic toggle-mechanism 41 comprises a pneumatic 43 in communication with the wind-chest through a conduit 44, two links 45 and 46 pivotally mounted at 47 and 48, respectively, on the leaves of the pneumatic 43 and pivotally connected together at 49, and a push-rod 50 pivotally connected to the link 45 at 51 and pivotally connected at 52 to a floating lever 53 which is pivotally connected at 54 to the push-rod 38. 75 80

The expression-device 42 for varying the operative position of the solo-action 16 during playing, comprises a pneumatic 55 for actuating the solo-action 16, a valve-mechanism 56 for controlling the pneumatic 55, 85 and a regulator-mechanism 57 for controlling the valve-mechanism 56.

The pneumatic 55 is pivotally connected at 58 with a rod 59 which is pivotally connected at 60 to the floating lever 53. A 90 spring 61 tends to hold the pneumatic 55 in expanded position.

The valve-mechanism 56 comprises a chamber 62 in communication with the pneumatic 55 through the conduit 63, a flap-valve 95 64 for controlling the atmospheric port 65 leading to the chamber 62, a flap-valve 66 for controlling the exhaust-port 67, and a valve-actuating rod 68 for actuating the valves 64 and 66. 100

A button 69 is secured on the rod 68 to limit the downward movement of the rod by engagement with the wall 70 of the chamber 62. This button 69 also serves to open the valve 64 by engagement with the finger 71 on the valve. A button 72 is secured on the rod 68, above the finger 71, for limiting the upward movement of the rod 68 by engagement with an abutment 73. The button 69 is so located that, when it engages the wall 70, the valve 66 will uncover the exhaust-port 67. The button 72 is so located that, when it engages the abutment 73, the button 69 will lift the valve 64 to uncover the atmospheric port 65. The upper end of the rod 68 is pivoted at 74 to a floating lever 75, one end of which is pivoted at 76 to a rod or link 77 which is pivotally connected at 78 to an arm 79 secured to, and extending from, the movable leaf of the pneumatic 55. 110 The other end of the floating lever 75 is pivotally connected at 80 to a rod or link 81, the upper end of which is pivotally connected at 82 to a bellows or pneumatic 83 forming part of the regulator-mechanism 57. 115 120

The regulator-mechanism 57 comprises, in addition to the bellows 83, a port-block 85 located inside the bellows 83, a knife-valve 86 controlling the port 87 of the port-block 130

85, a link 88 having one end pivotally connected to the knife-valve 86 and the other end pivotally connected to the movable leaf of the bellows 83, and a spring 84 tending 5 to hold the bellows 83 in expanded position. The port 87 is in communication with the pump 14 through the conduit 89, regulator 90, conduit 91, conduit 28, and conduit 27. The interior of the bellows 83 is in communication 10 with a plurality of openings 92 in the tracker 19 through the conduit 93, which has a plurality of branches 94, one for each of the tracker-openings 92. The openings 92 are in transverse line, respectively, with 15 the openings 30, so that they may be controlled by the same perforations in the music-sheet, as hereinafter more fully described.

The exhaust-port 67 is in communication 20 with the conduit 89 through a conduit 95.

The regulator 90 may be of any usual or suitable type and comprises a bellows 96 in communication with the conduit 89, a port-block 97 having a port in communication 25 with the conduit 91, a knife-valve 98 for controlling the port in the port-block 97 and actuated by the movable leaf of the bellows 96, and a spring 99 tending to hold the bellows 96 in expanded position. The function 30 of this regulator 90 is to maintain a substantially constant air-pressure in the conduit 89, regardless of changes of pressure in the conduit 28.

In order that the expression-device 42 may 35 be manually controlled, when desired, the conduit 93 is provided with a branch 100 (Fig. 1) which leads to a port-block 101 (Fig. 3) having a port 102 controlled by means of a valve 103 which may be actuated 40 in any suitable manner, as by means of a hand-lever 104 to which the valve may be connected by means of a link 105.

If desired, the communication between the pneumatic 43 and the wind-chest through 45 the conduit 44 may be controlled by means of a valve-mechanism 106 which is controlled by the tail-stock 107 for the music-spool 23, the construction being such that, when a music-spool of a certain length is 50 placed in position, the tail-stock 107 will be shifted to actuate the valve-mechanism 106 to open communication between the pneumatic and the wind-chest, such a construction being described in detail in Klugh Patent No. 1,261,553 referred to above.

A hammer-rest-rail 108 may be provided to determine the position of the solo-playing hammers.

The operation is as follows: Assuming 60 that the instrument is idle and it is desired to play a selection, the music-spool 23 is placed in position in the roll-box. This opens the valve-mechanism 106, placing the pneumatic 43 and conduit 44 in communication 65 with the wind-chest. The motor 25 is

then started, to cause the pump 14 to withdraw air from the wind-chest through the conduits 26 and 27, from the expression-device 15 through the conduit 28, and from the regulator-mechanism 57 through the conduit 89, regulator 90, and conduit 91. The withdrawal of air from the wind-chest causes the collapse of the pneumatic 43 and a consequent raising of the push-rod 38 through the action of the pivoted links 45 70 and 46, the push-rod 50, and the floating lever 53. The lifting of the push-rod 38 swings the solo-action 16 into operative position, in which all of the hammer-heads 33 are held close to the strings in short stroke-position by means of the rests 32.

The pneumatic 83 of the regulator-mechanism 57 is also collapsed, as the air supply through the conduit 93 is cut off by the music-sheet and air is exhausted from the pneumatic through the conduit 89. The pneumatic 83, therefore, collapses until the knife-valve 86 practically closes the port 87. This lifts the valve-actuating rod 68 through the action of the rod 81 and the floating lever 75. This lifting of the valve-actuating rod 68 permits the valve 66, controlling the exhaust-port 67, to close, and opens the valve 64 controlling the atmospheric port, thus placing the pneumatic 55 in communication with the atmosphere through the port 65, chamber 62, and conduit 63. The pneumatic 55 accordingly remains expanded for the present, under the action of the spring 61.

As the music-sheet travels over the tracker 19, the note-perforations 1^a register with the openings 18 in the tracker, causing the actuation of the corresponding pneumatics 17 of the player-action, and, hence, the sounding of the corresponding notes. If it is desired that a certain note be emphasized with respect to other notes being sounded at the same time, the note-perforation 1^b in the music-sheet, corresponding to the note to be emphasized, is made wide enough to uncover the corresponding opening 35 in the tracker. When this opening 35 is uncovered, it causes the collapse of the corresponding pneumatic 31 of the solo-action 16, which moves the corresponding rest or abutment 32 away 100 from the piano-strings, permitting the corresponding hammer-heads 33 to fall back to long stroke-position against the hammer-rest-rail 108. When the perforation which has uncovered the opening 35 registers with 105 the corresponding tracker-opening 18, the note is sounded with emphasis because the hammer has fallen back to long stroke-position.

In order to obtain desired variations in 110 the degree of rarefaction of the air in the wind-chest, the music-sheet is provided with suitable perforations 1^c for registration with the apertures or openings 30 in the tracker 19. There are five degrees of air- 115

pressure which may thus be obtained. With all of the openings 30 covered, the degree of rarefaction is the least; with the right-hand openings 30 uncovered, the degree of rarefaction is greater; with the second opening from the right uncovered, the degree of rarefaction is still greater; and so on, the degree of rarefaction being greatest with the left-hand openings 30 uncovered. The construction of the expression-device 15 is such that the degree of rarefaction obtained by uncovering one of the tracker-openings 30 is not affected by the uncovering of any of the tracker-openings 30 to its right; that is to say, the degree of rarefaction obtained is the same when only the left-hand tracker-opening 30 is uncovered as it would be if all of the tracker-openings 30 were uncovered, and the degree of rarefaction obtained if the next to the left-hand opening 30 is uncovered alone is the same as it would be if this opening 30 were uncovered and also both of the openings 30 to the right of it, etc. This construction is taken advantage of in the operation of the expression-device, as will be hereinafter pointed out.

Coming now to the operation of the expression-device 42, there are five positions of the solo-action 16 which may be obtained by the operation of this device. With all of the tracker-openings 92 covered, the solo-action will, when the instrument is being played, be held in position to maintain the hammers in their shortest stroke-position; with one of the openings 92 uncovered (and it is immaterial which one), the solo-action will swing to permit the hammers to fall back a little farther from the strings; with two of the openings 92 uncovered (and it is immaterial which two), the solo-action will swing to let the hammers fall still farther back; with three openings uncovered, the hammers will be permitted to swing still farther back; and with four of the openings 92 uncovered, the solo-action will be swung to give the greatest length of stroke for the accompaniment-playing hammers.

It will be understood that this swinging of the solo-action controls only the accompaniment-playing hammers, and that, in any position of the solo-action, the solo-playing hammers are permitted to fall back against the hammer-rest-rail 108.

Assuming that the instrument is being played and that all of the tracker-openings 92 are covered, the pneumatic 83 of the regulator mechanism 57 will be collapsed, the valve 64 will be open, the valve 66 will be closed, the pneumatic 55 will be expanded, and the pivotal point 60 will be in its highest position, which will hold the solo-action 16 in a position to maintain the accompaniment-playing hammers in their shortest stroke-position. For convenience, the different positions in which the accompaniment-playing hammers

may be held will be referred to as first, second, third, fourth, and fifth positions; the first position being the shortest stroke-position, and the fifth position being the longest stroke-position. Also, for convenience, the different degrees of rarefaction of air in the wind-chest, caused by the operation of the expression-device 15, will be referred to as first, second, third, fourth, and fifth degrees of pressure; the first degree of pressure indicating the lowest degree of rarefaction of air, and the fifth degree of pressure indicating the highest degree of rarefaction.

As previously noted, the tracker-openings 92 are in line with the tracker-openings 30, respectively, and the openings 92 are controlled from the same perforations in the music-sheet which control the openings 30. This results in a saving in the length of the tracker, and prevents disturbing existing standards in the music-sheet and tracker, while it theoretically limits the number of variations in air-pressure and hammer-stroke-length otherwise possible, this limitation is not material from a practical standpoint. These limitations are such that, with the second degree of air-pressure, the accompaniment-playing hammers can occupy only the second stroke-position—that is, they cannot occupy the third, fourth, or fifth stroke-positions; with the third degree of air-pressure, the accompaniment-playing hammers can be made to occupy only the second or third stroke-positions—that is, they cannot be made to occupy either the fourth or fifth stroke-positions; with the fourth degree of air-pressure, the accompaniment-playing hammers can be made to occupy the second, third, or fourth stroke-positions; and, with the fifth degree of air-pressure, the accompaniment-playing hammers can be made to occupy the second, third, fourth or fifth stroke-positions. As, in practice, it is never desirable that the tone-volume or tonal power of the accompaniment should be greatly varied during soft playing of the solo, this limitation is not material from a practical standpoint.

Assuming, now, that it is desired that the air-pressure should be of the second degree and that the accompaniment-playing hammers should occupy the second stroke-position, the music-sheet is perforated so that a perforation will register with the right-hand tracker-openings 92 and 30, as viewed in Fig. 5. This admits air through the right-hand tracker-opening 92 into the pneumatic 83, which has been in collapsed position, and causes this pneumatic 83 to expand to open the knife-valve 86 until the amount of the valve-opening is sufficient to permit the air to be drawn off through the conduit 89 as fast as it is supplied through the tracker-opening 92. This opening of the

pneumatic 83 closes the valve 64 and opens the valve 66, through the operation of the rod 81 and the floating lever 75. The opening of the valve 66 and closing of the valve 64 causes a collapsing movement of the pneumatic 55, the air being exhausted therefrom through the conduit 63 and exhaust-port 67. This collapsing movement of the pneumatic 55 continues until it causes the closing of the valve 66, through the operation of the arm 79, the rod 77, and the floating lever 75.

In effect, the pivotal connection 80 of the floating lever 75 assumes a definite position corresponding to the uncovering of a single one of the tracker-openings 92, and the pneumatic 55 assumes a definite position corresponding to this position of the pivotal point 80.

As previously stated, the button 69 limits the opening movement of the valve 66 and, consequently, the degree of rapidity with which the pneumatic 55 collapses. By adjusting this button 69, the rapidity of collapse of the pneumatic 55 may be regulated. If this adjustment of the button 69 is such that it stops the opening or expanding movement of the pneumatic 83 before said pneumatic has assumed a position of equilibrium, in which the air will be withdrawn just as fast as it is supplied, said pneumatic will continue its opening or expanding movement as soon as the pivotal point 76 of the floating lever 75 is raised by the collapse of the pneumatic 55, and this opening movement of the pneumatic 83 will continue until said pneumatic reaches the aforesaid position of equilibrium.

Assume, now, that it is desired that the air-pressure should be of the fifth degree, and that the accompaniment-playing hammers should be in the fourth position. To accomplish this, the music-sheet is provided with a perforation which will register with the left-hand openings 92 and 30, and it is also provided with two additional perforations (in transverse alignment on the music-sheet with the first perforation referred to) which will register with two of the other openings 92 in the tracker. This will cause air to be admitted to the pneumatic 83 through three of the tracker-openings 92, which will cause the pneumatic 83 to open to its next to widest position, and will, consequently, cause the pneumatic 55 to collapse to a corresponding extent, which will move the solo-action 16 to a position in which the accompaniment-playing hammers will be held in the fourth position.

The uncovering of the left-hand tracker-opening 30 will cause the fifth degree of air-pressure, and, as previously described, the uncovering of the other tracker-openings 30 to the right of the left-hand opening will not affect the degree of air-pressure.

In connection with the operation of the expression-device 42, it will be observed that the regulator-mechanism 57 will tend to assume one of five different positions (which one depending on whether none, one, two, three, or four of the tracker-openings 92 are uncovered), and that there will thus be five definite positions of the pivotal connection 80 of the floating lever 75. As a consequence, there will be five definite positions of the pneumatic 55, and five different definite positions of the solo-action 16.

If the accompaniment-playing hammers were, for instance, in fifth stroke-position (which would mean that all of the tracker-openings 92 were uncovered), and it was desired to move the solo-action to a position corresponding to third stroke-position, and it was at the same time desired to maintain an air-pressure of the fifth degree, the music-sheet perforation uncovering the left-hand openings 92 and 30 would be continued to maintain the desired fifth degree of air-pressure, but two of the three other perforations would be discontinued, it being immaterial which two. The flow of air from the tracker to the pneumatic 83 would thus be cut down from the capacity of four openings to that of two openings, and this would result in a collapsing movement of the pneumatic 83 and a consequent lifting of the pivotal connection 80 of the floating lever 75. This adjustment of the floating lever 75 would open the valve 64 and close the valve 66, causing an expansion of the pneumatic 55, due to the action of the spring 61, the pneumatic 55 being in communication with the atmosphere through the conduit 63, chamber 62, and atmospheric port 65. This opening movement of the pneumatic 55 would continue until the valve 64 was closed through the operation of the arm 79 (secured to the movable leaf of the pneumatic 55) and the link 77 connected with the floating lever 75. The degree of rapidity with which the pneumatic 55 expands is controlled by means of and may be regulated by adjustment of the button 72, which engages the abutment 73 to limit the opening movement of the valve 64. In case the button 72 engages the abutment 73 before the pneumatic 83 has collapsed sufficiently to restore a state of equilibrium between the air supplied to the pneumatic and the air exhausted therefrom, said pneumatic 83 will continue its collapsing movement as soon as the pivotal connection 76 of the floating lever 75 is lowered on account of the expansion of the pneumatic 55.

It will be observed that the change in degree of air-pressure affects both the accompaniment-playing hammers and the solo-playing hammers, whereas the change in position of the solo-action affects only the accompaniment-playing hammers. By 130

means of this construction, the tone-volume or tonal power of the accompaniment may be made to approach or recede from the tone-volume or tonal power of the solo.

5 For manually controlling the position of the solo-action 16, the hand-lever 104 is shifted to move the valve 103 to the left or right (as shown in Fig. 3) to admit air more or less freely to and thus control the 10 position of the regulator-mechanism 57.

10 The regulator-mechanism 57 controls the pneumatic 55 and associated parts, as described in connection with the sheet-controlled action.

15 In the construction shown in Figs. 7 to 11, inclusive, the casing 10, piano-action 11, player-action 12, selector-mechanism 13, air-pump 14, expression-device 15, and solo-action 16 may be substantially the same as 20 in the construction just described.

25 The pneumatic 55, the valve-mechanism 56, the regulator-mechanism 57, and the connections between these parts may also be substantially the same as in the construction shown in Figs. 1 to 6, inclusive.

30 In this form, however, the pneumatic 55 is connected with the hammer-rest-rail 108 instead of to the swinging solo-action, and the supply of air to the regulator-mechanism 57 is controlled by means of the primary valves of the expression-device 15. The solo-action 16 is moved to operative position by means of a pneumatic toggle-mechanism 109, and the operative position 35 of the solo-action is varied by means of the reservoir 110, which is in communication, through the port 112, with the wind-chest 111, with which the player-action 12 communicates. In this form of my invention, 40 the pump and connections for the wind-chest 111 may be substantially the same as in the form shown in Fig. 1, the wind-chest 111 being in communication with the pump through conduits similar to the conduits 26 and 27 of Fig. 1. The communication of 45 the reservoir 110 with the wind-chest 111, and the communication of the pneumatic 113 of the pneumatic toggle-mechanism with the wind-chest, are controlled by 50 means of a valve-mechanism 114 (Fig. 8), which valve-mechanism is controlled by the tail-stock 115 for the music-spool 23. This valve-mechanism may be similar to that shown in the patent to Klugh 1,261,553, 55 dated April 2, 1918, mechanical musical instruments, and is shown in detail in Figs. 12 and 13. Referring to Figs. 8, 12 and 13, a conduit 115^a extends from the action wind-chest (not shown) to the valve-mechanism 114 associated with the tail-stock 115 for the music-spool 23. This valve-mechanism 114 comprises a pair of blocks 115^e and 115^d having ducts or passages 115^e and 115^f, respectively, terminating in ports 115^g and 115^h, respectively. The block 115^e is

5 pivotally mounted so that it may be swung with reference to the block 115^d to bring the ports 115^g and 115^h into and out of register with each other. A spring 115ⁱ tends to swing the block 115^e into a position 10 to the right, as shown in dotted lines in Fig. 12, in which position the ports 115^g and 115^h will be out of register so that no communication can be established between the conduit 115^a, connecting with the block 115^e, and the conduit 115^k connected with the block 115^d and extended from the same 15 to the pneumatic 113. The tail-stock 115 for the music-spool has an extension 115^l adapted to extend to and act upon the block 115^e, and the music-spool 23 has a projecting collar 115^m (Figs. 12 and 14) which, when the music-spool is in position, pushes said tail-stock 115 sufficiently to the left (Fig. 12) to cause the extension 115^l 20 to move the block 115^e into position to cause the ports 115^g and 115^h to register with one another; this whole arrangement being of course one arrangement or mechanism for controlling pneumatic communication to the pneumatic 113 of the pneumatic toggle-mechanism. The tail-stock 115 is subject to a spring 115ⁿ tending to force said tail-stock to the right (Fig. 12) 25 to press the same against the music-spool end. The music-spool 23 is understood to carry a music-roll particularly adapted for playing solo music which brings into operation the solo mechanism, the solo rolls being provided with such extended or projecting spool-collars 115^m as are shown in the drawings (Figs. 14 and 15).

30 The valve-mechanism 106 may be similar in all respects to the valve-mechanism 114 described above.

35 Referring now, in detail, to the construction whereby the primary valves of the expression-device 15 control the flow of air to the regulator-mechanism 57, the conduit 116 leads from the regulator-mechanism 57 40 to a header 117 (Figs. 9 and 10). This header 117 is in communication with four passages, 118, 119, 120, and 121, controlled, respectively, by four primary valves, such as 122, the primary valves being, in turn, 45 controlled, respectively, from the tracker-openings 123, 124, 125, and 126 (Fig. 11) 50 through four conduits, such as 123^a (Fig. 7).

55 Each of the passages 118, 119, 120, and 121 is provided with a check-valve 127, which will permit the flow of air from the respective passage into the header but will prevent the flow of air from the header back into the passage, so that air will not be sucked out of the regulator-mechanism 57 60 through the conduit 116 when any or all of the passages 118, 119, 120, and 121, are connected with the wind-chest 128 of the primary valves.

65 The relation of the tracker-openings 123, 130

124, 125, and 126 to the expression-device 15 is substantially the same as is the relation of the tracker-openings 30 to the expression-device in the form shown in Figs. 1 to 6, inclusive;—that is to say, if none of the openings 123, 124, 125, and 126 are uncovered, air is admitted with the greatest degree of freedom to the wind-chest of the player; if the opening 123 is uncovered, air is admitted with a lesser degree of freedom; if the opening 124 is uncovered, air is admitted with a still lesser degree of freedom; and so on, with the other two tracker-openings, air being admitted with the least degree of freedom when the left-hand tracker-opening 126 is uncovered.

The more freely air is admitted to the wind-chest, the less will be the degree of rarefaction of the air in the wind-chest. As stated in connection with Figs. 1 to 6, the construction of the expression-device 15 is such that the degree of rarefaction obtained by uncovering one of the tracker-openings is not affected by the uncovering of any of the other tracker-openings to its right. This construction is taken advantage of in this control of the regulator-mechanism 57, as well as in the control previously described.

There are five positions of the hammer-rest-rail 108 which may be obtained by the operation of the regulator-mechanism 57, just as, in the construction shown in Figs. 1 to 6, inclusive, there are five positions of the solo-action 16 which may be obtained by the operation of the regulator-mechanism 57. With all of the tracker-openings 123, 124, 125, and 126 covered, the hammer-rest-rail 108 will, when the instrument is being played, be held in position to maintain the solo-hammers in the shortest stroke-position; with one of the openings 123, 124, 125, or 126 uncovered (and it is immaterial which one), the hammer-rest-rail 108 will swing to permit the hammers to fall back a little farther from the strings; with two of the openings 123, 124, 125, and 126 uncovered (and it is immaterial which two), the hammer-rest-rail will swing to permit the solo-hammers to fall back still farther; and so on.

It will be understood that the swinging of the hammer-rest-rail controls only the solo-playing hammers, and that, in any position of the hammer-rest-rail, the accompaniment-playing hammers are controlled by the solo-action 16.

It is understood, of course, that the amount of air admitted through tracker-openings 123, 124, 125 and 126, is dependent, to a considerable extent, upon the correct registration of the several respective music-sheet-perforations therewith, and that part of the air so admitted is drawn through conduits 126^a and the vents of the primary

valve-action into wind-chest 128 (Fig. 9). These vents are fixed in size and, consequently, the difference between the amount of air admitted through the described sheet-controlled tracker-openings 123, 124, 125 70 and 126, and the amount of such air drawn through the vents into wind-chest 128 would vary considerably with a slight variation in the lateral position of the music-sheet. This described difference in amounts is all that 75 would be available for the conduit 116, if the passages 118, 119, 120 and 121 were directly connected with the tracker-openings 123, 124, 125 and 126, and I have, therefore, shown the passages as controlled by the primary valves 122, since it is desirable that the flow of air through each of said passages should not be affected by variations in the lateral position of the music-sheet.

If desired, a manually-operated valve, 85 such as shown in Fig. 3, may be connected with conduit 116 in the same manner and for the same purpose as it is shown (Fig. 1) and described in connection with conduit 93.

Coming now to the construction and operation of the mechanism for controlling the swinging solo-action, this may be substantially the same as that shown in the herein-before mentioned Klugh Patent No. 1,261, 553, except that, in the present device, there 95 is a valve-controlled communication between the reservoir 110 and the wind-chest 111. This valve-controlled communication is provided for the reason that, when some music-rolls which are not "soloized" are being 100 used, it is desirable that the reservoir 110 be cut off from communication with the wind-chest 111 in order to get the desired musical effect, while, when "soloized" music is being played, it is important that there 105 shall be communication between the reservoir and the wind-chest. By "soloized" music-roll is meant a music-roll which, when used with the instrument shown, will cause solo effects to be produced.

The mechanism for controlling the position of the solo-action comprises the pneumatic 113, links 130 and 131 pivotally connected together at 132 and pivotally connected to the leaves of the pneumatic 113 at 133 115 and 134, respectively, a lift-rod 135 pivotally connected to the link 131, a lever 136 actuated by the lift-rod 135, a lift-rod 137 actuated by the lever 136, a V-shaped spring 138 exerting an upward pressure on the 120 lower end of the lift-rod 137, a bell-crank-lever 139 for drawing down or lowering the lift-rod 137, and an arm 140 secured to the movable leaf of the reservoir 110 for engaging and operating the bell-crank-lever 125 139. A V-shaped spring 141 is interposed in the connection between the lift-rod 135 and the lever 136 to permit the lowering of the lift-rod 137 without lowering lift-rod 135. The lever 136 is pivotally mounted at 130

142 on any suitable support. The bell-crank-lever 139 is mounted in suitable bearings 143.

The mechanism for controlling the port 5 112 between the reservoir 110 and the wind-chest 111 comprises a flap-valve 144, a pneumatic 145 for actuating the flap-valve 144, and a push-rod 146 for transmitting motion from the pneumatic 145 to the flap-10 valve 144.

The pneumatics 145 and 113 will both be collapsed, upon rarefaction of air in the action wind-chest, if a "soloized" music-roll has been placed in position in the roll-box. 15 This is accomplished by the engagement of the tail-stock 115 for the music-spool with the valve-mechanism 114, which connects the conduit 115^k (which is in communication with the pneumatics 113 and 145 through 20 the branches 148 and 149) with the action wind-chest through the conduit 115^a.

The operation of the mechanism for swinging the solo-action is as follows: Assuming that the air-pump is working and 25 that there is rarefied air in the wind-chest, the placing of a "soloized" music-roll in position in the roll-box will cause the collapse of the pneumatics 113 and 145. The collapse of the pneumatic 113 moves the swinging solo-action 16 to bring the hammers of the piano-action to their shortest stroke-position, through the medium of the pivoted links 130 and 131, the lift-rod 135, the spring 141, the lever 136, and the lift-rod 137. 30 With air-pressure in the wind-chest corresponding to a lesser tonal power than that of mezzo-forte, the solo-action will remain in this position. If, however, the rarefaction of air in the wind-chest is increased 35 beyond that corresponding to mezzo-forte, the reservoir 110 will be collapsed thereby to a degree which brings the arm 140 into engagement with the vertical arm of the bell-crank-lever 139 and actuates this bell-40 crank-lever to force the rod 137 downwardly, against the action of the springs 138 and 141, thus causing the solo-action to be moved to permit the piano-hammers to fall back to a longer stroke-position. The 45 greater the increase of rarefaction of the air in the wind-chest over that corresponding to mezzo-forte, the greater will be the stroke-lengths of the accompaniment-hammers. The solo-hammers are, of course, permitted to fall back against the hammer-rest-rail 108 by the collapse of the pneumatics of 50 the solo-action.

The variations in solo and accompaniment which may be obtained are as follows: 60 Both solo and accompaniment are influenced by the degree of rarefaction of the air in the wind-chest, which determines the power exerted by the striker-pneumatics on the piano-action. The accompaniment is 65 also influenced by the position of the solo-

action, which, in turn, is controlled by the degree of rarefaction of the air in the wind-chest. The degree of rarefaction of the air in the wind-chest thus has a double effect on the accompaniment; it determines the 70 force exerted by the striker-pneumatics and also determines the stroke-lengths of the accompaniment-hammers. The degree of rarefaction of the air is selectively determined by the perforations in the music-sheet which 75 control the tracker-openings 123, 124, 125, and 126. The solo, in addition to being influenced by the air-pressure, is also influenced by the position of the hammer-rest-rail 108, the position of the hammer-rest-rail being determined by the instant number 80 of perforations in the music-sheet controlling the tracker-openings 123, 124, 125, and 126.

As explained in connection with Figs. 1 to 6, inclusive, the position of the regulator-mechanism 57 may be varied independently of the variations in air-pressure, in spite of the fact that the perforations which control the regulator-mechanism 57 register with 90 the tracker-openings which control the air-pressure. This independent variation is possible because only one of the series of transversely aligned perforations in the music-sheet, registering with the tracker 95 openings 123, 124, 125, and 126, is effective in determining the air-pressure, whereas all of the transversely aligned perforations are effective in determining the position of the regulator-mechanism 57.

By means of this control of the hammer-rest-rail 108 through the regulator-mechanism 57, the tonal power of the solo may be made to approach or recede with respect to the tonal power of the accompaniment, and 105 may be varied independently of the variations in the accompaniment.

In the construction shown in Figs. 7 to 11, inclusive, not only is the regulator-mechanism 57 controlled from perforations in the 110 music-sheet which register with the tracker-openings which control the air-pressure, but the regulator-mechanism 57 is controlled from the same tracker-openings as control the air-pressure.

While, from this description, the control of the "solo" and that of the "accompaniment" appear to be very similar and of little distinctive value, the one over the other, there is, in fact, a wide distinction 120 therebetween, not only in the musical effects obtainable thereby, but because the employment of one method of control, rather than the other, in automatic musical instruments is, of necessity, more than simple 125 preference. In some instruments, one of these methods might be necessary to produce the desired results and the other would be impracticable, while, in other instruments, the reverse condition might obtain. 130

The principles of construction of the various instruments are controlling in such matters to a greater or less degree.

While I have shown and claimed my invention as used upon a player-piano, it is to be understood that its use is not necessarily so limited. It may be used in connection with other musical instruments where a control of the degree of movement of the note-sounding mechanism may effect expression-control.

In the claims, where the term "regulator" is used, it is meant to be understood as meaning an automatically operating, valve-adjusting device which acts automatically upon a variation of air-pressure to position the valve in conformity with such variation. Also, where the term "one expression part of a musical composition" is used, it is meant to refer to a part of the music such as the solo part, the accompaniment part, the principal theme, the subsidiary theme, and other such musically separable or distinguishable parts of a musical composition, as distinguished from the first, middle, or latter part thereof.

I claim as new and desire to secure by Letters Patent of the United States:

1. An expression-device for an automatic musical instrument, comprising means for mechanically adjusting parts of the musical instrument to limit the movements of the note-sounding mechanism, said means including a regulator.

2. An expression-device for an automatic musical instrument, comprising means for mechanically adjusting parts of the musical instrument to limit the movements of the note-sounding mechanism, said means including a regulator and means through which said regulator is controlled in operation from the note-sheet.

3. An expression-device for an automatic musical instrument, comprising a regulator for mechanically adjusting parts of the musical instrument to limit the movements of the note-sounding mechanism, and means through which said regulator is controlled in operation from the note-sheet in a permutative manner.

4. An expression-device for an automatic musical instrument, comprising a regulator for mechanically adjusting parts of the musical instrument to limit the movements of the note-sounding mechanism, and means through which said regulator is controlled in operation by selective means of the note-sheet which are employed to control the operation of devices other than said expression-device.

5. An expression-device for a player-piano, comprising means for mechanically adjusting parts of the player-piano to limit the travel of the piano-hammers, said means including a regulator.

6. An expression-device for a player-piano, comprising means for mechanically adjusting parts of the player-piano to limit the travel of the piano-hammers, said means including a regulator and means through which said regulator is controlled in operation from the note-sheet.

7. An expression-device for a player-piano, comprising a regulator for mechanically adjusting parts of the player-piano to limit the travel of the piano-hammers, and means through which said regulator is controlled in operation from the note-sheet in a permutative manner.

8. An expression-device for a player-piano, comprising a regulator for mechanically adjusting parts of the player-piano to limit the travel of the piano-hammers, and means through which said regulator is controlled in operation by selective means of the note-sheet which are employed to control the operation of devices other than said expression-device.

9. In a mechanical musical instrument having sheet-controlled means for emphasizing one expression part of a musical composition with respect to another part thereof, means acting to mechanically adjust parts of the instrument to limit movements of the note-sounding mechanism to vary the emphasis given to said one expression part of the musical composition, the last said means including a pneumatic regulator.

10. In a mechanical musical instrument having sheet controlled means for emphasizing one expression part of a musical composition with respect to another part thereof, means acting to mechanically adjust parts of the instrument to limit movements of the note-sounding mechanism to vary the emphasis given to said one expression part of the musical composition, the last said means including a pneumatic regulator and means through which said regulator is controlled in operation from the note-sheet.

11. In a mechanical musical instrument having sheet-controlled means for emphasizing one expression part of a musical composition with respect to another part thereof, a pneumatic regulator acting to mechanically adjust parts of the instrument to limit movements of the note-sounding mechanism to vary the emphasis given to said one expression part of the musical composition, and means through which said regulator is controlled in operation from the note-sheet in a permutative manner.

12. In a mechanical musical instrument having sheet-controlled means for emphasizing one expression part of a musical composition with respect to another part thereof, a pneumatic regulator acting to mechanically adjust parts of the instrument to limit movements of the note-sounding mechanism to vary the emphasis given to said one expression-device.

pression part of the musical composition, and means through which said regulator is controlled in operation by selective means of the note-sheet, which selective means are employed to control the operation of other devices.

13. In a player-piano having sheet-controlled means for emphasizing one expression part of a musical composition with respect to another part thereof, means acting to mechanically adjust parts of the instrument to limit the travel of the piano-hammers to vary the emphasis given to said one expression part of the musical composition, the last said means including a pneumatic regulator.

14. In a player-piano having sheet-controlled means for emphasizing one expression part of a musical composition with respect to another part thereof, means acting to mechanically adjust parts of the instrument to limit the travel of the piano-hammers to vary the emphasis given to said one expression part of the musical composition. 25 the last said means including a pneumatic regulator, and means through which said regulator is controlled in operation from the note-sheet.

15. In a player-piano having sheet-controlled means for emphasizing one expression part of a musical composition with respect to another part thereof, a pneumatic regulator acting to mechanically adjust parts of the instrument to limit the travel of the piano-hammers to vary the emphasis given to said one expression part of the musical composition, and means through which said regulator is controlled in operation from the note-sheet in a permutative manner.

16. In a player-piano having sheet-controlled means for emphasizing one expression part of a musical composition with respect to another part thereof, a pneumatic regulator acting to mechanically adjust parts of the instrument to limit the travel of the piano-hammers to vary the emphasis given to said one expression part of the musical composition, and means through which said regulator is controlled in operation by selective means of the note-sheet, which selective means are employed to control the operation of other devices.

17. In a mechanical musical instrument having sheet-controlled means for emphasizing one expression part of a musical composition, means acting to mechanically adjust parts of the instrument to limit movements of the note-sounding mechanism to vary the tonal power of a part, other than the emphasized expression part, of said musical composition, the last said means including a pneumatic regulator.

18. In a mechanical musical instrument having sheet-controlled means for emphasizing one expression part of a musical com-

position, means acting to mechanically adjust parts of the instrument to limit movements of the note-sounding mechanism to vary the tonal power of a part, other than the emphasized expression part, of said musical composition, and means through which said regulator is controlled in operation from the note-sheet.

19. In a mechanical musical instrument having sheet-controlled means for emphasizing one expression part of a musical composition, a pneumatic regulator acting to mechanically adjust parts of the instrument to limit movements of the note-sounding mechanism to vary the tonal power of a part, other than the emphasized expression part, of said musical composition, and means through which said regulator is controlled in operation from the note-sheet in a permutative manner.

20. In a mechanical musical instrument having sheet-controlled means for emphasizing one expression part of a musical composition, a pneumatic regulator acting to mechanically adjust parts of the instrument to limit movements of the note-sounding mechanism to vary the tonal power of a part, other than the emphasized expression part, of said musical composition, and means through which said regulator is controlled in operation by selective means of the note-sheet, which selective means are employed to control the operation of other devices.

21. In a player-piano having sheet-controlled means for emphasizing one expression part of a musical composition, means acting to mechanically adjust parts of the instrument to limit the travel of the piano-hammers to vary the tonal power of a part, other than the emphasized expression part, of said musical composition, the last said means including a pneumatic regulator.

22. In a player-piano having sheet-controlled means for emphasizing one expression part of a musical composition, means acting to mechanically adjust parts of the instrument to limit the travel of the piano-hammers to vary the tonal power of a part, other than the emphasized expression part, of said musical composition, the last said means including a pneumatic regulator and means through which said regulator is controlled in operation from the note-sheet.

23. In a mechanical musical instrument having means for emphasizing one expression part of a musical composition through a limitation of the movements of certain units of the note-sounding mechanism of said instrument, means controlled in operation from the note-sheet to vary the degree of limitation of such units as have the more limited movements.

24. In a mechanical musical instrument having means for emphasizing one expression part of a musical composition through

- a limitation of the movements of certain units of the note-sounding mechanism of said instrument, means controlled in operation from the note-sheet to vary the degree 5 of limitation of such units as have the more limited movements, and means through which the last said means are controlled in operation from the note-sheet in a permutative manner.
- 10 25. In a mechanical musical instrument having means for emphasizing one expression part of a musical composition through a limitation of the movements of certain units of the note-sounding mechanism of 50 said instrument, means controlled in operation from the note-sheet to vary the degree of limitation of such units as have the more limited movements, and means through which the last said means are controlled in 55 operation by selective means of the note-sheet, which selective means are employed to control the operation of other devices.
26. In a player-piano having means for emphasizing one expression part of a musical composition through a limitation of the movements of certain hammers of the piano-action of said instrument, means controlled in operation from the note-sheet to vary the degree of limitation of such hammers as 60 have the more limited movements.
27. In a player-piano having means for emphasizing one expression part of a musical composition through a limitation of the movements of certain hammers of the piano-action of said instrument, means controlled in operation from the note-sheet to vary the degree of limitation of such hammers as have the more limited movements, and means through which the last said 65 means are controlled in operation from the note-sheet in a permutative manner.
28. In a player-piano having means for emphasizing one expression part of a musical composition through a limitation of the movements of certain hammers of the piano-action of said instrument, means controlled in operation from the note-sheet to vary the degree of limitation of such hammers as have the more limited movements, and 70 means through which the last said means are controlled in operation by selective means of the note-sheet, which selective means are employed to control the operation of other devices.
29. In a mechanical musical instrument having means for emphasizing, as a class, the notes of one expression part of a musical composition through a limitation, as a class, of the units of the note-sounding mechanism 75 used to sound notes of another part of said composition, means controlled in operation from the note-sheet to vary the degree of such limitation.
30. In a mechanical musical instrument 80 having means for emphasizing, as a class, the notes of one expression part of a musical composition through a limitation, as a class, of the units of the note-sounding mechanism used to sound notes of another part of said composition, means controlled in operation from the note-sheet to vary the degree of such limitation, and means through which the last said means are controlled in operation from the note-sheet in a permutative manner.
31. In a mechanical musical instrument having means for emphasizing, as a class, the notes of one expression part of a musical composition through a limitation, as a class, of the units of the note-sounding mechanism used to sound notes of another part of said composition, means controlled in operation from the note-sheet to vary the degree of such limitation, and means through which the last said means are controlled in operation by selective means of the note-sheet, which selective means are employed to control the operation of other devices.
32. In a player piano having means for emphasizing, as a class, the notes of one expression part of a musical composition through a limitation, as a class, of certain hammers of the piano-action used to sound notes of another part of said composition, means controlled in operation from the note-sheet to vary the degree of such limitation.
33. In a player-piano having means for emphasizing, as a class, the note of one expression part of a musical composition through a limitation, as a class, of certain hammers of the piano-action used to sound notes of another part of said composition, means controlled in operation from the note-sheet to vary the degree of such limitation, and means through which the last said means are controlled in operation from the note-sheet in a permutative manner.
34. In a player-piano having means for emphasizing, as a class, the notes of one expression part of a musical composition through a limitation, as a class, of certain hammers of the piano-action used to sound notes of another part of said composition, means controlled in operation from the note-sheet to vary the degree of such limitation, and means through which the last said means are controlled in operation by selective means of the note-sheet, which selective means are employed to control the operation of other devices.
35. The combination, in a mechanical musical instrument having sheet-controlled means for emphasizing certain notes, of a note-sheet provided with selective means of one character for selecting for emphasis notes of the solo or melody part of a musical composition, and with selective means of another character for selecting notes of the accompaniment of said composition, and means controlled in operation from said 130

note-sheet to vary the tonal power of the accompaniment, as such.

36. The combination, in a mechanical musical instrument having sheet-controlled means for emphasizing certain notes, of a note-sheet provided with selective means for selecting the notes to be emphasized and for selecting other notes not to be emphasized, and means controlled in operation from said

note-sheet to vary, as a class, the tonal power of the said other notes not to be emphasized.

37. The combination, in a mechanical musical instrument having sheet-controlled means for subduing certain notes, of a note-sheet provided with selective means for selecting, to be subdued, notes of the accompaniment part of a musical composition, and means controlled in operation from said note-sheet to vary the degree to which said notes of the accompaniment parts are subdued.

38. An automatic musical instrument comprising a note-sounding action; means for emphasizing one expression part of a musical composition, comprising a plurality of independently movable abutments, each acting mechanically on certain units of said note-sounding action to limit the movement thereof, a plurality of pneumatics for actuating said abutments, respectively, and a common support for said abutments and pneumatics, said pneumatics in expanded position causing the units to be held in limited stroke-position and in collapsed position permitting the units to assume longer stroke-position; and sheet-controlled means for moving said common support to vary the limited stroke-position.

39. A sheet-controlled pneumatic player-piano comprising a piano-action; means for emphasizing one expression part of a musical composition, comprising a plurality of independently movable abutments, each acting mechanically on one or more piano-action-units to control the length of stroke thereof, a plurality of pneumatics for actuating said abutments, respectively, and a common support for said abutments and pneumatics, said pneumatics in expanded position causing the hammers to be held in short stroke-position and in collapsed position permitting the hammers to fall back to long stroke-position; and sheet-controlled actuating-means for moving said common support to vary the short stroke-position.

40. A sheet-controlled pneumatic player-piano comprising a piano-action; means for emphasizing one expression part of a musical composition, comprising a plurality of independently movable abutments, each acting mechanically on one or more piano-action-units to control the length of stroke thereof, a plurality of pneumatics for actuating said abutments, respectively, and a common support for said abutments and

pneumatics, said pneumatics in expanded position causing the hammers to be held in short stroke-position and in collapsed position permitting the hammers to fall back to long stroke-position; sheet-controlled actuating-means for moving said common support to vary the short stroke-position; and abutment-means for limiting the long stroke-position of the hammers.

41. A sheet-controlled pneumatic player-piano comprising a piano-action; means for emphasizing one expression part of a musical composition, comprising a plurality of independently movable abutments, each acting mechanically on one or more piano-action-units to control the length of stroke thereof, a plurality of pneumatics for actuating said abutments, respectively, and a pivotally mounted common support for said abutments and pneumatics, said pneumatics in expanded position causing the hammers to be held in short stroke-position and in collapsed position permitting the hammers to fall back to long stroke-position; and sheet-controlled actuating-means for moving said common support to vary the short stroke-position.

42. A sheet-controlled pneumatic player-piano comprising a piano-action; means for emphasizing one expression part of a musical composition, comprising a plurality of independently movable abutments, each acting mechanically on one or more piano-action-units to control the length of stroke thereof, a plurality of pneumatics for actuating said abutments, respectively, and a common support for said abutments and pneumatics, said pneumatics in expanded position causing the hammers to be held in short stroke-position and in collapsed position permitting the hammers to fall back to long stroke-position; sheet-controlled actuating-means for moving said common support to vary the short stroke-position; and actuating-means for moving said common support to move said abutments from inoperative to operative position.

43. A sheet-controlled pneumatic player-piano comprising an air-pump; a piano-action; means for emphasizing one expression part of a musical composition, comprising a plurality of independently movable abutments, each acting mechanically on one or more piano-action-units to control the length of stroke thereof, a plurality of pneumatics for actuating said abutments, respectively, and a common support for said abutments and pneumatics, said pneumatics in expanded position causing the hammers to hold in short stroke-position and in collapsed position permitting the hammers to fall back to long stroke-position; sheet-controlled actuating-means for moving said common support to vary the short stroke-position; and actuating-means for moving

- said common support to move said abutments from inoperative to operative position, comprising a pneumatic in communication with said air-pump.
- 5 44. An automatic musical instrument comprising an air-pump; note-sounding mechanism; a device movable to a plurality of different positions for limiting the movement of certain units of said note-sounding mechanism; and means for controlling the movement of said device, comprising a pneumatic in communication with said air-pump, a valve controlling said communication and controlled by said pneumatic, and means for admitting air to said pneumatic.
- 10 45. A sheet-controlled musical instrument comprising an air-pump; note-sounding mechanism; a device movable to a plurality of different positions for limiting the movement of certain units of said note-sounding mechanism; and means for controlling the movement of said device, comprising a pneumatic in communication with said air-pump, a valve controlling said communication and controlled by said pneumatic, and sheet-controlled means for admitting air to said pneumatic.
- 15 46. A sheet-controlled pneumatic player-piano comprising an air-pump; a tracker; a piano-action; a device movable to a plurality of different positions for limiting the movement of certain units of said piano-action; and means for controlling the movement of said device, comprising a pneumatic in communication with said air-pump, a valve controlling said communication and controlled by said pneumatic, and means affording communication between said pneumatic and a plurality of tracker-openings.
- 20 47. A sheet-controlled pneumatic player-piano comprising an air-pump; a tracker; a device movable to a plurality of different positions for controlling the expression; means for controlling the movement of said device, comprising a pneumatic in communication with said air-pump, a valve controlling said communication and controlled by said pneumatic, and means affording communication between said pneumatic and a plurality of tracker-openings; and a second expression-controlling device controlled from the same tracker-openings.
- 25 48. A sheet-controlled pneumatic player-piano comprising an air-pump, a tracker, a device movable to a plurality of different positions for controlling the expression, means for controlling the movement of said device comprising a pneumatic in communication with said air-pump and with a plurality of tracker-openings; and a second expression-controlling device controlled from the same tracker-openings.
- 30 49. A sheet-controlled musical instrument comprising a note-sounding mechanism; sheet-controlled means for emphasizing one expression part of a musical composition with respect to another part thereof, comprising a plurality of independently movable devices, each acting mechanically on one or more units of said note-sounding units, and sheet-controlled modulating means acting collectively and mechanically on a plurality of note-sounding mechanism, whereby more than two different degrees of tone-volume of one of said parts may be obtained.
- 35 50. A sheet-controlled player-piano comprising a piano-action; sheet-controlled means for emphasizing the solo part of a musical composition with respect to the accompaniment part thereof, comprising a plurality of independently movable devices, each acting mechanically on one or more piano-action-units; and sheet-controlled modulating-means acting collectively and mechanically on a plurality of piano-action-units, whereby a plurality of different degrees of tone volume of the accompaniment may be obtained.
- 40 51. A sheet-controlled pneumatic player-piano comprising a piano-action; means for emphasizing one expression part of a musical composition, comprising a plurality of independently movable abutments, each acting mechanically on one or more piano-action-units to control the length of stroke thereof, a plurality of pneumatics for actuating said abutments, respectively, and a common support for said abutments and pneumatics, said pneumatics in expanded position causing the hammers to be held in short stroke-position and in collapsed position permitting the hammers to fall back to long stroke-position; and means for moving said common support, comprising a floating lever, sheet-controlled actuating-means for moving one end of said lever to vary the short stroke-position, and actuating-means for moving said other end of said lever to move the abutments from inoperative to operative position.
- 45 52. A sheet-controlled pneumatic player-piano comprising a piano-action; means for emphasizing one expression part of a musical composition, comprising a plurality of independently movable abutments, each acting mechanically on one or more piano-action-units to control the length of stroke thereof, a plurality of pneumatics for actuating said abutments, respectively, and a common support for said abutments, said pneumatics in expanded position causing the hammers to be held in short stroke-position and in collapsed position permitting the hammers to fall back to long stroke-position; sheet-controlled actuating-means for moving said common support to vary the short stroke-position; and actuating-means

for moving said common support to move said abutments from inoperative to operative position.

53. A sheet-controlled pneumatic player-piano comprising a piano-action; means for emphasizing one expression part of a musical composition, comprising a plurality of independently movable abutments, each acting mechanically on one or more piano-action-units to control the length of stroke thereof, a plurality of pneumatics for actuating said abutments, respectively, and a common support for said abutments, said pneumatics in expanded position causing the hammers to be held in short stroke-position and in collapsed position permitting the hammers to fall back to long stroke-position; and means for moving said common support, comprising a floating lever, sheet-controlled actuating-means for moving one end of said lever to vary the short stroke-position, and actuating-means for moving the other end of said lever to move said abutments from inoperative to operative position.

54. In a player-piano having sheet-controlled means for emphasizing one expression part of a musical composition, a pneumatic regulator acting to mechanically adjust parts of the instrument to limit the travel of the piano-hammers to vary the tonal power of a part, other than the emphasized expression part, of said musical composition, and means through which said regulator is controlled in operation from the note-sheet in a permutative manner.

55. In a player-piano having sheet-controlled means for emphasizing one expression part of a musical composition, a pneumatic regulator acting to mechanically adjust parts of the instrument to limit the travel of the piano-hammers to vary the tonal power of a part, other than the emphasized expression part, of said musical composition, and means through which said regulator is controlled in operation by selective means of the note-sheet, which selective means are employed to control the operation of other devices.

56. A sheet-controlled pneumatic musical instrument comprising an air-pump, a storage-reservoir in communication with said air-pump, and means controlled by the music-spool for controlling the communication between said air-pump and storage reservoir.

57. A sheet-controlled pneumatic musical instrument comprising an air-pump, a storage-reservoir in communication with said air-pump, and means controlled by placing the music-spool in position with respect to said instrument for controlling the communication between said air-pump and storage reservoir.

58. A sheet-controlled pneumatic musical

instrument comprising an air-pump, a reservoir in communication with said air-pump, a valve controlling communication between said air-pump and reservoir, a pneumatic controlling said valve, and means controlled by placing the music-spool in position with respect to said instrument for controlling said pneumatic.

59. A sheet-controlled pneumatic musical instrument comprising an expression-device, an air-pump, a pneumatic in communication with said air-pump for controlling said expression-device, a reservoir in communication with said air-pump for additionally controlling said expression-device, and means for controlling the communication between said reservoir and air-pump.

60. A sheet-controlled pneumatic musical instrument comprising an expression-device, an air-pump, a pneumatic in communication with said air-pump for controlling said expression-device, a reservoir in communication with said air-pump for additionally controlling said expression-device, and means controlled by the music-spool for controlling the communication between said reservoir and air-pump.

61. A sheet-controlled pneumatic musical instrument comprising an expression-device, an air-pump, a pneumatic in communication with said air-pump for controlling said expression-device, a reservoir in communication with said air-pump for additionally controlling said expression-device, and means controlled by placing the music-spool in position with respect to said instrument for controlling the communication between said air-pump and reservoir.

62. A sheet-controlled pneumatic musical instrument comprising a solo-action, an air-pump, a pneumatic in communication with said air-pump for moving said solo-action into operative position, a reservoir in communication with said air-pump for controlling the position of said solo-action, and means for controlling the communication between said air-pump and reservoir.

63. A sheet-controlled pneumatic musical instrument comprising a solo-action, an air-pump, a pneumatic in communication with said air-pump for moving said solo-action into operative position, a reservoir in communication with said air-pump for controlling the position of said solo-action, and means controlled by placing the music-spool in position with respect to said instrument for controlling the communication between said air-pump and reservoir.

64. In an automatic musical instrument, the combination of a note-sounding action; means for emphasizing one expression part of a musical composition with respect to another part thereof, comprising a plurality of independently-movable abutments, each acting mechanically upon one or more

movable units of said action to control the limit of movement thereof, and a plurality of pneumatics for actuating said abutments, respectively; and means for limiting the effective action of said abutments; with sheet-controlled means for moving said limiting means to thereby vary the degree of emphasis to be given one of said parts of the musical composition with respect to 10 another part thereof.

65. An automatic musical instrument comprising an air-pump; note-sounding mechanism; a device movable to a plurality of different positions for limiting the movement of certain units of said note-sounding mechanism; and means for controlling the movement of said device, comprising a pneumatic in communication with said air-pump, a valve controlling said communication and 15 controlled by said pneumatic, and means for admitting varying amounts of air to said pneumatic.

66. A sheet-controlled musical instrument comprising an air-pump; note-sounding mechanism; a device movable to a plurality of different positions for limiting the movement of certain units of said note-sounding mechanism; and means for controlling the movement of said device, comprising a pneumatic in communication with said air-pump, a valve controlling said communication and 20 controlled by said pneumatic, and sheet-controlled means for admitting varying amounts of air to said pneumatic.

35 67. An automatic musical instrument comprising a tracker, note-sounding mechanism, and two independently variable expression-devices for controlling said note-sounding mechanism; both said expression-40 devices being controlled from the same tracker opening.

68. An automatic musical instrument comprising a tracker, note-sounding mechanism; and two independently variable expression-devices for controlling said note-sounding mechanism; both said expression-devices being simultaneously controlled from the same tracker-opening.

69. A player-piano comprising a tracker, 50 a piano-action, and two independently variable expression-devices for controlling said piano-action; both said expression-devices being controlled from the same track-opening.

55 70. A player-piano comprising a tracker, a piano-action, and two independently variable expression-devices for controlling said piano-action; both said expression-devices being simultaneously controlled from the 60 same tracker-opening.

71. An automatic musical instrument comprising a note-sounding action; sheet-controlled means for emphasizing the solo part of a musical composition with respect to 65 the accompaniment part thereof, compris-

ing a plurality of independently movable devices, each acting mechanically on one or more note-sounding action-units; and sheet-controlled modulating means acting collectively and mechanically on a plurality of 70 note-sounding action-units, whereby a plurality of different degrees of tone volume of the accompaniment may be obtained.

72. The combination, with a tracker having a plurality of expression-openings, and 75 an expression-device controlled from said plurality of expression-openings, said expression-device being of a type in which its control through one of said expression-openings is independent of its control through another of said expression-openings, of a second expression-device controlled from the same expression-openings, said second expression-device being of a type in which its control through one of said expression-openings is modified by its control through another of said expression-openings.

73. A sheet-controlled pneumatic musical instrument comprising an air-pump, a pump-reservoir in communication with said air-pump, and means controlled by the music-spool for controlling the communication of said air-pump with said pump-reservoir.

74. A sheet-controlled pneumatic musical 95 instrument comprising a player-action, a reservoir for affecting the wind-pressure for operating the player-action, and means controlled by the music-spool for controlling said communication of said reservoir with 100 said player-action.

75. The combination, with an automatic musical instrument comprising a tracker having openings, note-sounding mechanism, and two independently variable expression-devices for controlling said note-sounding mechanism, of a note-sheet having perforations for registration with said openings; both said expression-devices being controlled from the same note-sheet perforation.

76. The combination, with an automatic musical instrument comprising a tracker, note-sounding mechanism and two independently variable expression-devices for controlling said note-sounding mechanism, of a note-sheet having selective devices for cooperation with said tracker; both said expression-devices being controlled from said same selective device of said note-sheet.

77. An expression-device for an automatic musical instrument, comprising means for mechanically adjusting parts of the musical instrument to limit the movements of the note-sounding mechanism, conduits through 115 which said means may be controlled in adjustment, and means connected with said conduits for controlling the first said means by varying the number of active conduits.

78. An expression-device for an automatic 130

- musical instrument, comprising means for mechanically adjusting parts of the musical instrument to limit the movements of the note-sounding mechanism, selective devices 5 through which said means may be controlled in adjustment, and means co-operating with said selective devices for controlling the first said means by varying the number of active selective devices.
- 10 79. An expression-device for an automatic musical instrument comprising means for mechanically adjusting parts of the musical instrument to limit the movements of the note-sounding mechanism, a moving controller having selective devices, conduits through which said means may be controlled in adjustment and means connected with said conduits for controlling the first said means by varying the number of selective devices 15 of said controller which co-operate with said conduits.
- 15 80. An expression-device for an automatic musical instrument having a tracker with a plurality of openings, comprising means for mechanically adjusting parts of the musical instrument to limit the movements of the note-sounding mechanism, and means whereby the first said means may be controlled by varying the number of uncovered 20 tracker-openings.
- 25 81. An expression-device for a player-piano, comprising means for mechanically adjusting parts of the player-piano to limit the travel of the piano-hammers, a tracker having a plurality of openings, and means whereby the first said means may be controlled by varying the number of uncovered 30 tracker-openings.
- 35 82. An expression-device for an automatic musical instrument, comprising a regulator for mechanically adjusting parts of the musical instrument to limit the movements of the note-sounding mechanism, a tracker having a plurality of openings, and means whereby said regulator may be controlled by varying the number of uncovered 40 tracker-openings.
- 45 83. An expression-device for an automatic musical instrument, comprising a regulator for mechanically adjusting parts of the musical instrument to limit the movements of the note-sounding mechanism, and means for controlling said regulator by admitting varying amounts of air thereto.
- 50 84. An automatic musical instrument comprising note-sounding mechanism, an expression-device for controlling said note-sounding mechanism comprising a regulator, and a moving controller having selective devices 55 for controlling said note-sounding mechanism and other selective devices for controlling said regulator.
- 60 85. An expression-device for an automatic musical instrument, comprising means for mechanically adjusting parts of the musical instrument to limit the movements of the note-sounding mechanism, a moving controller having selective devices for controlling said regulator.
- 65 86. A tracker-controlled expression-controlling device, a tracker, pressure-operable devices controlled in operation from said tracker, an air-connection between said device and said devices, and means co-operating with said tracker to control the operation of said pressure-operable devices to vary the volume of air passing through said air-connection to effect the control of said expression-controlling device.
- 70 87. A tracker-controlled expression-controlling device, a tracker, fluid-controlled operable devices controlled in operation from said tracker, a fluid-transmitting connection between said device and said devices, and means co-operating with said tracker to control the operation of said fluid-controlled operable devices to vary the volume of fluid passing through said connection to effect the control of said expression-controlling device.
- 75 88. The combination, with means for producing a flow of fluid, of means for mechanically adjusting parts of a musical instrument to limit the movements of the note-sounding mechanism thereof, a device susceptible to and operable by variations in fluid-pressure to any degree of adjustment between its extremes, said device being arranged to control the operation of said adjusting means, and means for applying and varying the application of fluid-pressure to said device, whereby varying limitations of the note-sounding mechanism may be obtained.
- 80 89. The combination, with means for producing a flow of fluid, of means for mechanically adjusting parts of a player-piano to limit the travel of the piano-hammers, a device susceptible to and operable by variations in fluid-pressure to any degree of adjustment between its extremes, said device being arranged to control the operation of said adjusting means, and means for applying and varying the application of fluid-pressure to said device, whereby varying limitations of the travel of the piano-hammers may be obtained.
- 85 90. The combination, with an air-pump, of means for mechanically adjusting parts of a musical instrument to limit the movements of the note-sounding mechanism thereof, a device susceptible to and operable by variations in air-pressure to any degree of adjustment between its extremes, said device be-
- 90 95 100 105 110 115 120 125 130

ing arranged to control the operation of said adjusting means, and means for applying and varying the application of air-pressure to said device, whereby varying limitations 5 of the note-sounding mechanism may be obtained.

91. The combination, with an air-pump, of means for mechanically adjusting parts of a player-piano to limit the travel of the piano-hammers, a device susceptible to and operable by variations in air-pressure to any degree of adjustment between its extremes, said device being arranged to control the operation of said adjusting means, and means for 10 applying and varying the application of air-pressure to said device, whereby varying limitations of the travel of the piano-hammers may be obtained.

92. An expression-device for an automatic musical instrument, comprising means for mechanically adjusting parts of the musical instrument to limit the movements of the note-sounding mechanism, a tracker having two sets of openings, conduits identified with 25 and corresponding to said sets of openings, whereof certain conduits corresponding to one of said sets of openings are connected with one another, and a device having a connection with said connected conduits and 30 controlling said means.

93. An expression-device for a player-piano, comprising means for mechanically adjusting parts of the player-piano to limit the travel of the piano-hammers, a tracker 35 having two sets of openings, conduits identified with and corresponding to said sets of openings, whereof certain conduits corresponding to one of said sets of openings are connected with one another, and a device 40 having a connection with said connected conduits and controlling said means.

94. An expression-device for an automatic musical instrument, comprising means for mechanically adjusting parts of the musical instrument to limit the movements of the note-sounding mechanism, a pneumatic for 45 controlling said means, and means for supplying variable air-pressure to said pneumatic, the last said means comprising a tracker having two sets of openings, and conduits identified with and corresponding to said sets of openings, certain of said conduits corresponding to one of said sets of 50 openings being connected with one another and with said pneumatic.

95. The combination, with a tracker having two sets of openings, and conduits identified with and corresponding to said sets of openings, whereof certain conduits corresponding to one of said sets of openings are 60 connected with one another, of an expression-device comprising means for mechanically adjusting parts of a musical instrument to limit the movements of the note-sounding mechanism thereof, pneumatic 65

mechanism connected with and controlling said expression-device, said pneumatic mechanism being connected with and operable from said connected conduits, whereby said expression-device is adjusted in accordance with the number of opened openings of 70 said one of said sets of openings, and other means for controlling the operation of said pneumatic mechanism.

96. In combination with a music-sheet 75 and a tracker having a plurality of openings, a fluid controlled hammer-stroke-adjusting device, and means controlled through the openings of said tracker for varying the hammer-stroke adjustment by said device in accordance with the number of uncovered tracker-openings.

97. In combination with a music-sheet 80 and a tracker having a plurality of openings, a fluid-controlled device for mechanically adjusting parts of a musical instrument to limit the movements of the note-sounding mechanism thereof, and means controlled through the openings of said tracker for varying the adjustment of said parts by 85 said device in accordance with the number of uncovered tracker-openings.

98. An expression-device for an automatic musical instrument, comprising means for mechanically adjusting parts of the musical 90 instrument to limit the movements of the note-sounding mechanism, said means including a regulator and manually operable means for controlling said regulator.

99. An expression-device for an automatic 100 musical instrument, comprising means for mechanically adjusting parts of the musical instrument to limit the movements of the note-sounding mechanism, said means including a regulator and manually operable 105 means for controlling the amount of air admitted to said regulator.

100. An expression-device for an automatic musical instrument, comprising means for mechanically adjusting parts of the musical 110 instrument to limit the movements of the note-sounding mechanism, an air-passage-controller, and means whereby the first said means may be controlled by determining the amount of air allowed to pass 115 said air-passage-controller.

101. An expression-device for an automatic musical instrument, comprising means for mechanically adjusting parts of the musical instrument to limit the movements 120 of the note-sounding mechanism, an air-admission-conduit, and means whereby the first said means may be controlled by determining the amount of air admitted to said air-admission-conduit.

102. An expression-device for an automatic musical instrument, comprising means for mechanically adjusting parts of the musical instrument to limit the movements 125 of the note-sounding mechanism, a fluid-

- passage-controller, and means whereby the first said means may be controlled by determining the amount of fluid allowed to pass said fluid-passage controller.
- 5 103. An expression-device for an automatic musical instrument, comprising means for mechanically adjusting parts of the musical instrument to limit the movements of the note-sounding mechanism, a fluid-admission-conduit, and means whereby the first said means may be controlled by determining the amount of fluid admitted to said fluid-admission-conduit.
- 10 104. A fluid-regulator having a movable member, and means for determining the position of the movable member, comprising manually controlled means for determining the amount of fluid admitted to the regulator.
- 15 105. The combination with an element to be adjusted, of a device for adjusting said element comprising a pressure-chamber having a movable wall, two passages to said chamber, a valve controlling one of said passages, and manual means for controlling the other of said passages; said element and valve being arranged for adjustment by movement of said wall.
- In witness whereof, I have hereunto subscribed my name.
- J. CLARKE HAGEY.

Certificate of Correction.

It is hereby certified that in Letters Patent No. 1,422,969, granted July 18, 1922, upon the application of James Clarke Hagey, of Chicago, Illinois, for an improvement in "Expression Devices for Automatic Musical Instruments," errors appear in the printed specification requiring correction as follows: Page 1, line 27, for the compound word "tracker-opening" read *tracker-openings*; page 4, lines 4 and 9, for the word "openings" read *opening*, and line 87, after the word "tracker" strike out the comma and insert a period; line 88, capitalize the "w" in "while"; page 10, line 71, claim 18, after the word "composition" insert the phrase *the last said means including a pneumatic regulator*; page 13, line 71, claim 49, for the word "units" read *mechanism*, and line 73, after the word "of" insert the words *units of said*; same page, line 109, claim 51, for the word "said", first occurrence, read *the*, and line 110, for the article "the" read *said*; page 15, line 98, claim 74, for the article "the" read *said*, and line 100, for the word "said", first occurrence, read *the*; line 119, claim 76, for the word "said" read *the*; and that the said Letters Patent should be read with these corrections therein that the same may conform to the records of the case in the Patent Office.

Signed and sealed this 31st day of October, A. D., 1922.

[SEAL.]

KARL FENNING,
Acting Commissioner of Patents.
